UNITED STATES PATENT OFFICE.

GEORGE W. DOVER, OF CRANSTON, RHODE ISLAND.

BUTTON.

SPECIFICATION forming part of Letters Patent No. 636,960, dated November 14, 1899.

Application filed August 29, 1899. Serial No. 728,923. (No model.)

To all whom it may concern:

Be it known that I, GEORGE W. DOVER, a citizen of the United States, residing at Cranston, Providence county, and State of Rhode Island, have invented a new and useful Improvement in Buttons, of which the following is a specification.

My invention relates to that class of buttons in which the use of solder is dispensed with; and its object is to secure a maximum stiffness in a button without increasing the weight thereof, which end I secure by the novel arrangement of parts disclosed in the accompanying drawings, in which—

15 Figure 1 is a perspective view of my button shoe and post; Fig. 2, a plan view of the head-pieces; Fig. 3, a side view of the post with the head-pieces applied thereto; Figs. 4 and 5, perspective views of the button parts after the setting-up operations. Fig. 6 is a plan view of Fig. 5, and Fig. 7 a vertical sectional view of completed button.

Similar letters refer to similar parts throughout the several views.

25 To the hollow tapering post *a* of my button I apply two concavo-convex plates *b* *c*, Fig. 2, in such a manner that the periphery of the lower plate *c* contacts with that of the upper plate *b*, which latter plate differs from the former in that it is pierced centrally with an angular opening rather than with one circular in form, as shown in plate *c*, which prevents the plate *b* from turning on the post. The parts now present the arrangement shown in 35 Fig. 3, wherein the top of post *a* (lettered *d* in said figure) projects some distance beyond the plate *b*. I next enlarge the cylindrical projection *d* by the downward stroke of a pyramidal-shaped tool to the form shown at *d'*, Fig. 4, and by a second downward stroke with greater force press the material outwardly until it rests closely upon the plate *b*, as at *d''*, Fig. 5, to whose upper contour it conforms. I complete the button-head by applying a face-cap *e* in the usual manner. It will be seen that the resulting button has a great degree of stiffness, due to the mutual relations of the parts, which are so disposed as

to distribute the strain brought to bear upon the button-head, the lower head-plate being 50 held in place by friction with the post, which friction is increased by any force applied to the post, whose laterally-projecting extremity tends to force the upper upon the lower plate. Thus all the parts reciprocally unite to stiffen 55 the button.

I am aware that prior to my invention buttons have been made without the use of solder to unite their parts. I therefore do not claim this feature as my invention. 60

What I do claim as my invention, and desire to secure by Letters Patent, is—

1. A button comprising a tapering post, two concavo-convex plates with their convex surfaces outermost each secured to the post, and 65 a third plate extending over the upper of said plates constituting a face-plate.

2. A button comprising a tapering post, two concavo-convex plates with their convex surfaces outermost secured to the post by lateral 70 projections extending from the post upon the outer surface of the upper plate, and a face-plate extending over the upper plate.

3. A button comprising a tapering post, two concavo-convex plates with their convex surfaces outermost secured to the post by lateral 75 projections extending from the post upon the outer surface of the upper plate, and a face-plate extending over the upper plate and bent in under the outer edge of the lower plate. 80

4. A button comprising a tapering hollow post, two concavo-convex plates with their convex surfaces outermost carried by said post, the upper of said plates having an angular opening through which the post passes, 85 projections extending from the post upon the outer surface of the upper plate, and a face-plate extending over the upper plate.

In testimony whereof I have subscribed my name to this specification in the presence of 90 two witnesses:

GEORGE W. DOVER.

In presence of—

RETA M. DOVER,
HORATIO E. BELLows.
